CLAIM

(52) U.S. Cl. **D14/356**; D14/363

The ornamental design for a magnetic disk memory device for electronic computers, as shown and described.

(58) **Field of Search** D14/356, 363,

DESCRIPTION

D14/364, 365, 367; D13/162, 184, 199;

FIG. 1 is a top, front and right side perspective view of a magnetic disk memory device for electronic computers showing my new design,

312/223.1-223.3; 360/99.01-99.12; 361/690-696;

FIG. 2 is a front elevational view thereof,

369/34.01, 36.01

FIG. 3 is a top plan view thereof,

(56) **References Cited**

FIG. 4 is a right side elevational view, a left side elevational view being a mirror image.

U.S. PATENT DOCUMENTS

FIG. 5 is a rear elevational view thereof; and,
